Primary Examiner — Jack Reickel*Assistant Examiner* — Michael A Kervin(74) *Attorney, Agent, or Firm* — Michael Best & Friedrich LLP(57) **CLAIM**

We claim the ornamental design for a rake, as shown and described.

DESCRIPTION

FIG. 1 is a perspective view of a rake showing our new design.

FIG. 2 is another perspective view of the rake of FIG. 1.

FIG. 3 is a front view of the rake of FIG. 1.

FIG. 4 is a rear view of the rake of FIG. 1.

FIG. 5 is a right side view of the rake of FIG. 1.

FIG. 6 is a left side view of the rake of FIG. 1.

FIG. 7 is a top view of the rake of FIG. 1; and,

FIG. 8 is a bottom view of the rake of FIG. 1.

The broken line showing of a rake is for the purpose of illustrating portions of the article and forms no part of the claimed design.

1 Claim, 6 Drawing Sheets(56)
